UNITED STATES PATENT OFFICE.

EDWARD L. ADREON, JR., OF ST. LOUIS, MISSOURI.

TIE-PLATE.

1,073,078.

Specification of Letters Patent.

Patented Sept. 9, 1913.

Original application filed June 6, 1910, Serial No. 565,319. Divided and this application filed May 27, 1912. Serial No. 700,096.

To all whom it may concern:

Be it known that I, EDWARD L. ADREON, Jr., a citizen of the United States, and resident of St. Louis, Missouri, have invented 5 certain new and useful Improvements in Tie-Plates, of which the following is a specification containing a full, clear, and exact description, reference being had to the accompanying drawings, forming a part 10 hereof.

My invention relates to improvements in tie plates, and the object of my invention is to provide a tie plate having a plurality of spaced apart projections on its upper face 15 and adjacent each side margin of the plate. The innermost ends of the projections aline in rows paralleling the side margins of the plate in order to form shoulders against which the side margins of the rail-base may 20 engage. Certain of the projections are perforated to receive spikes which may be driven through the plates, their heads overlapping and engaging the base of the rail and the material of the projections outside 25 of the spike openings serving as a backing for the shank of the spike.

This is a divisional application from the application filed by me on June 6, 1910, Serial No. 565,319.

30 With the above purposes in view my invention consists in certain novel features of construction and arrangement of parts as will be hereinafter more fully described, pointed out in the claims and illustrated by 35 the accompanying drawings, in which—

Figure 1 is a plan of a length of material from which tie plates may be sheared; Fig. 2 is a plan of one of my improved plates sheared from a length of material as shown 40 in Fig. 1 and having the spike openings formed therein; Fig. 3 is a transverse, sectional elevation taken on the line 3—3 of Fig. 2; Fig. 4 is a plan illustrating a modified form of tie plate; and Fig. 5 is a transverse, sectional elevation taken on the line 45 5—5 of Fig. 4.

Referring by numerals to the accompanying drawings: 6 designates the body portion of the tie plate which provides a rail-bearing surface. Formed on the upper face 50 of the tie plate and integral therewith are the oppositely disposed projections 7, the inner margins 8 and 9 of which projections are arranged in alining rows on either side 55 of the rail-bearing surface and between

which rows of projections the rail base is placed. Certain, or if desired all, of the projections 7 are perforated in order to form spike openings 10, the spike openings being removed from the margins 8 of the 60 projections 7 on one side of the plate and formed through and including the margin 9 of the projections 7 on the other side of the plate, in order that the spikes driven in the last mentioned side of the plate will 65 have their shanks bear against the margin of the base of the rail. In plan each of the projections 7 is preferably triangular-shaped, or at least of such shape as will leave a portion of the side margins of the 70 head of a driven spike overlap a projection, 7 in order that a claw may be introduced under the head of the spike to draw the spike.

As shown in the drawings, especial attention being directed to Figs. 2 and 3, it is to be observed that the spike openings have a comparatively large backing for the shank of the spike to bear against, thus when a spike is being seated it is directed at all 75 times against the rail instead of away from the rail. It is to be observed further in Fig. 3 that the upper surfaces of each of the projections 7 incline downwardly and inwardly in order that screw spikes may be employed 80 in such manner that their heads will bear against the bases of the rails instead of against the upper surfaces of the projections.

In Figs. 4 and 5, the projections 7 are of 90 substantially the same shape as shown in my preferred form, except that they consist each of two converging walls 11 which are spaced apart in order that the spike openings 10 may be formed through the body 6 95 of the plate only, thereby simplifying punching or forming of the spike openings.

The plates of this invention are designed with especial attention given to the formation thereof by rolling, and for this reason 100 the projections on one side of the plate are out of registration with the projections on the other side of the plate, so that there will be substantially the same amount of material between the rollers forming the plates 105 at all times.

As shown in Fig. 2, there are spike openings 12 formed through the body portion 6 of the plates and are laterally removed from the projections 7 so that the spikes may be 110

driven through the plate to engage the bases of rails of different widths.

I claim:

1. A tie plate, pressed from a single piece 5 of material and provided with a series of separate projections, the inner walls of which are in alinement and form a maximum base for the edge of the rail; there being a spike opening formed through one of 10 said projections, and an auxiliary opening formed through the rail-bearing surface of the plate whereby said tie plates may be used on rails of different widths.

2. As a new article of manufacture, a tie 15 plate having a rail-bearing surface and adjacent the side margins of the rail-bearing surface a plurality of spaced-apart upward projections, there being spike openings formed through said projections and 20 through the rail-bearing surface.

3. As a new article of manufacture, a tie 25 plate having a rail-bearing surface and integral rows of spaced-apart projections on the upper surface of the tie plate contiguous to the side margins of the rail-bearing surface, there being spike openings formed through certain of the projections laterally removed from the line of the rail base, and there being spike openings formed through 30 certain other of the projections and through

the rail-bearing surface in line with the line of the rail base.

4. As a new article of manufacture, a tie 35 plate constructed of a single piece of material having a rail-bearing surface and having upward projections which are spaced apart and located in alinement with each other and adjacent each side margin of the rail-bearing surface, each of said projections being substantially triangular-shaped 40 in plan and their upper surfaces inclining downwardly and inwardly, there being spike openings formed through certain of said projections and the body of the plate wholly within the margins of said projections, there being spike openings formed through certain other of the projections and the body of the plate and located adjacent the inside margins of said projections, and there being spike openings formed through 45 the rail-bearing surface removed from said projections, substantially as shown and for the purposes stated.

In testimony whereof, I have signed my name to this specification, in presence of 50 two subscribing witnesses.

EDWARD L. ADREON, JR.
